UNITED STATES PATENT OFFICE.

ARTHUR PRIMROSE YOUNG, OF KENILWORTH, AND JOSEPH HUTT, OF COVENTRY, ENGLAND, ASSIGNEES TO GENERAL ELECTRIC COMPANY, A CORPORATION OF NEW YORK.

PICK-UP DEVICE.

Application filed January 14, 1927, Serial No. 161,132, and in Great Britain January 9, 1926.

Our present invention relates to gramophones and like talking machines and also to pick-up or sound producing apparatus of the kind wherein the vibrations of a 5 gramophone or like stylus are converted into corresponding electric oscillations, which can then be passed through headphones or loud-speakers, when required. These apparatus, as is well known, are reversible in 10 operation, that is, can be adapted for producing record cuts.

The main object of our invention is the provision of pick-up apparatus having a substantially aperiodic stylus-lever, and to 15 this end the lever is mounted without any spring control, and damping means are provided for suitably restraining the movement of the same. The damping arrangement may consist of a chamber the size of 20 which is adjustable and which contains a non-elastic damping material, such as cotton-wool, with a portion of the stylus lever or a member rigidly secured thereto located in the chamber. Any equivalent arrangement 25 may be used; for instance, a portion of the stylus-lever, preferably an end extending away from the needle end, or a member rigidly secured thereto, may be arranged between two adjustable washers of 30 non-elastic damping material.

Our invention further comprises the combination of a stylus-lever mainly or entirely supporting an operable member, that is, 35 diaphragm, coil, armature or the like, with damping means associated therewith which are non-resilient in their effect. In the case of sound producing apparatus said operable member is preferably a light, rigid, conically-shaped diaphragm, connected at its 40 apex to the stylus and with its periphery only loosely connected to the fixed structure if at all.

According to a further feature of our invention, apparatus for converting the mechanical vibration of a gramophone or like 45 stylus into equivalent electric oscillations, or vice versa, including a conductor or coil adapted to be moved in a uniform magnetic field in accordance with the vibrations of the 50 stylus, is arranged so that the center point of the conductor or coil is almost exactly above the fulcrum of the stylus-lever. With such an arrangement for a limited movement 55 of the needle, the movement of the coil or

conductor is substantially horizontal, and, 55 therefore, the use of means for specially centering the coil, which would probably introduce a resilient restoring force, is obviated.

Arrangements for applying our invention 60 to apparatus for converting the sound impressions of a gramophone or like record into corresponding electric oscillations, are shown in Figs. 1, 2, 3 and 4 of the accompanying drawings, which are sectional 65 or part sectional views, Figs. 1^a, 2^a, and 3^a being side views of the arrangements of Figs. 1, 2 and 3. Like reference numerals are used to indicate similar parts.

Referring to the drawings, and first to 70 Figs. 1 and 1^a, this construction comprises a pair of approximately C-shaped magnets 11 arranged in one plane with their air gaps 12 adjacent one to another. Preferably the main portions 13 of each magnet are permanent bar magnets of cobalt steel, the end limbs 14 adjacent the air gaps being of soft iron. These two C-shaped magnets are suitably clamped in fixed relation to one another. Located in the two air gaps is a coil 15 of 75 pancake form mounted upon a stylus-rod 16 coincident with the main axis perpendicular to the coil. The lower portion of the rod 16 may be freely hinged to the fixed structure, e. g., it may be provided with two 80 diametrically projecting points 17 adapted to rest in a pair of adjustable cups 18 carried by the means 19 clamping the C-shaped magnets together. The lower extremity of the 85 rod 16 is provided with any suitable device 90 21 for receiving and holding the stylus-needle 22. The upper extremity 23 of the rod is located in a chamber 24 conveniently formed between the two magnets and filled with a suitable damping material, such as 95 cotton-wool, and a screw plug 25 may be provided for closing one end of the chamber 24 and for adjusting the pressure of the packing.

In the arrangement of Figs. 2 and 2^a the 100 type of apparatus illustrated includes a pot-shaped magnetic circuit 11 having inner and outer pole-pieces 26 and 27, respectively, with an annular air gap 12 between. The coil 15 now of annular form is located in 105 the air-gap 12 and secured to the stylus-lever 16 approximately half way up. The stylus-lever 16 is bent as a bell-crank, the

lower portion being fulcrumed in the cups 18, almost exactly beneath the center point of the coil 15, carried by the bracket 28 fixed to the magnetic structure. As in the previous case, the lower extremity of the stylus-lever is adapted to receive and hold the needle 22 and the upper extremity 23 is located in an adjustable damping chamber 24.

10 Figs. 3 and 3' show a modification of the arrangement described in the preceding paragraph in which the stylus-lever 16 does not extend upwardly appreciably beyond the center of the coil 15. Secured to the stylus-lever is a bolt 29 perpendicular thereto which carries a plate 31 or the equivalent located between two adjustable washers 32, any suitable means being provided for clamping the washers against the plate and for reducing 20 or increasing the pressure between the washers and the plate. These means are here shown as being constituted by the plates 33 and 34 interconnected by the screws 35, plate 34 being secured to the structure through its 25 flange 36 and screws 37. Plate 31 may be provided with holes or slots to accommodate freely the screws 35.

In the arrangement shown in Fig. 4 the magnet 11 is a ring magnet arranged within 30 a non-magnetic casing 38. The inner pole piece 27 is connected to one face of the magnet by the magnetic strip 39, and the outer pole piece 26 is connected to the other face of the magnet by the magnetic strip 41. It 35 will readily be understood that the flux passes radially between the pole pieces 26 and 27 through the annular air gap 12. In the arrangement illustrated by Fig. 4, the inner pole piece 27 is slotted at one or more 40 places longitudinally as by saw-cuts and strips of a suitable material 42, for instance, rubber, are located in the slots and arranged to extend radially therefrom sufficiently to engage the interior of the former carrying 45 the coil 15. Preferably the slots are arranged symmetrically around the periphery of the inner pole piece in order to avoid any 50 tendency towards displacing the coil 15 when it oscillates. It will be noted that although 55 the strips 42 may be made from elastic material, yet they exert no spring control on the moving elements in the direction of their motion, but serve only to damp the movement of the same. If the coil were wound internally of the former it might be desirable to arrange the material 42 in the face of the outer pole piece 26, in order that

the same may rub against the relatively smooth former instead of the rougher coil. The screws 43 are provided for clamping 60 the magnetic strips 39, 41, the magnet 11, the non-magnetic body portion 44 and the casing 38 together.

In gramophones and the like provided with non-resilient damping devices according to the invention, the diaphragm may be of such size as to give the requisite volume of sound without the use of an amplifying sound horn. Alternatively a baffle may be used with a smaller diaphragm, such an 70 arrangement acting in particular to emphasize the lower tones.

What we claim as new and desire to secure by Letters Patent of the United States, is,—

1. A pick-up device comprising a magnet provided with pole pieces arranged to form a circular air gap, a pivoted member, a coil supported by said member and arranged to be moved to and fro in said air gap, a damping material arranged to restrain the movement of said member, and means operable to adjust the pressure between said material and said member.

2. A pick-up device comprising a magnet provided with pole pieces arranged to form an air gap, a pivoted member, a coil supported by said member and arranged to be moved to and fro in said air gap, means arranged to produce a substantially non-resilient restraint on the movement of said member and means for adjusting the pressure between said means and said member.

3. A pick-up device comprising a magnet provided with pole pieces arranged to form a circular air gap, a pivoted member, a coil supported by said member and arranged to be moved to and fro in said air gap, a body of cotton-wool arranged to restrain the movement of said member, and means for adjusting the pressure between said body and said member.

4. A pick-up device comprising a magnet, a pivoted member, a coil supported by said member and arranged to be moved between the poles of said magnet, a body of cotton-wool arranged to restrain the movement of said member, and means operable to adjust the pressure between said material and said member.

In witness whereof, we have hereunto set our hands this 29th day of December, 1926.

ARTHUR PRIMROSE YOUNG.
JOSEPH HUTT.
